W. A. CAGLEY

CREAM OR MILK CAN HARNESS FOR AUTOMOBILES

Filed Oct. 17, 1925

W. A. Cagley

384 Watson E. Coleman
Attorne

UNITED STATES PATENT OFFICE.

WALTER A. CAGLEY, OF KINGSLEY, IOWA.

CREAM OR MILK CAN HARNESS FOR AUTOMOBILES.

Application filed October 17, 1925. Serial No. 63,155.

This invention relates to devices for holding cans, and particularly milk or cream cans, upon the running board of an automobile.

5 The general object of the invention is to provide what I may term a harness for this purpose which will engage the neck and body of the milk can and hold it rigidly in place upon the running board and which involves no rack or carriage attached to the 10 running board and normally in the way of use of the running board.

A further object is to provide a device of this character which is adjustable to 15 different size milk cans and which is so constructed that the milk can may be drawn downward into rigid engagement with the running board so that it will not be tipped over or shaken loose by jolts or jars.

20 Other objects will appear in the course of the following description.

My invention is illustrated in the accompanying drawing, wherein:

Figure 1 is a side elevation of a milk can, 25 the running board of an automobile being shown in cross section and showing my milk can harness in elevation;

Figure 2 is an elevation as in Figure 1, the section being taken at right angles to the 30 section in Figure 1;

Figure 3 is a top plan view of the collar and the upper ends of the straps extending downward therefrom;

Referring to this drawing, it will be seen 35 that my device comprises a collar adapted to go around the neck of the milk can A, this collar being formed in two sections 10 and 11 engaged with each other by bolts or like fastening devices 12, the ends of the sections 40 of the collar overlapping so that the collar may be adjusted to make it smaller or larger to suit variations in the sizes of milk cans.

Attached to each section of the collar is the upper section 13 of a downwardly extending tug, as it may be termed, or brace. This upper section 13 below its point of attachment to the collar is outwardly and downwardly curved so as to fit over the curved top portion of the milk can and then 45 extends straight downward. The lower end is provided with a plurality of perforations 14.

Attached to the upper section of the tug is the lower section 15, which is also provided with a plurality of holes 14 which over-

lap the holes 14 of the upper section, and bolts or screws may be used to hold these upper and lower sections in engagement with each other and permit the vertical adjustment of the sections relative to each other. The 60 lower section 15 of each tub is angularly bent at its lower end, as at 16, to accommodate the flange of the milk can and this angular end 16 is formed with a perforation. Pivoted upon the lower end of each lower 65 section is the lower extremity of an angular lever 17 which is pivoted at 18 to the lower end of the tug section 15 and engaged with the heel of the angular lever 17 is a link 19 formed at its lower end with a hook. This 70 link extends through the perforations in the angular ends 16. The hooks 19 of the two levers are adapted to engage with eyes 20, having shanks 21 which extend down through the running board and pass through 75 washers 22 and carry the nuts 23. Thus these eyes may be held securely upon the running board and inasmuch as the eyes may be relatively small they will not project up above the surface of the running board to an 80 extent which will prevent the use of the running board for other purposes.

The levers are held in a raised position by means of spring latches 24 which are attached to the lower sections 15 of the tug 85 rods as illustrated. Chains 25 are also detachably connected to the lower sections 15 of the tugs, these chains being adapted to pass around the milk can so as to prevent any lateral movement of the lower portion of the milk can with reference to the tugs.

In the use of this device, the collar formed of the sections 10 and 11 is clamped around the milk can neck with the tug sections extending downward at diametrically opposite points of the milk can, and the hooks of the links 19 are engaged with the eyes 20, the levers being turned into a horizontal position at this time, and then 100 when the levers are turned upward so that the upper ends of the levers are engaged by the latches 24, the milk can harness will be drawn downward and the milk can will be firmly clamped in place upon the running board. By pushing the levers down, the milk can harness may be readily disengaged and the milk can removed. If the eyes 20 are removed from the running board, the apertures through which the 105

110

bolts of these eyes pass may be readily filled up by flat-headed bolts so as to leave the running board in proper condition for use.

I claim:—

- 5 1. A harness for holding milk cans upon a running board comprising a sectional collar adapted to be clamped around the neck of the can, each section having a tug extending downward therefrom, each tug being formed in sections adjustable upon each other, members engaged with the lower portions of the tugs and adapted to embrace the lower portion of the milk can, a lever mounted upon the lower end of each tug, 15 a link connected to the lever and having a hook, and eyes adapted to be attached to the running board and with which said hooks are adapted to engage.
- 20 2. A milk can harness for holding milk cans upon the running boards of automobiles comprising a sectional collar adapted to be engaged around the neck of a milk can, downwardly extending tugs attached at their upper ends to the collar and formed 25 in sections longitudinally adjustable upon each other, levers, one for each lower section of the tug, each lever being angular at

its lower end and being pivoted at its extremity to the tug, a hooked link engaged with the heel of each lever, and eyes adapted to be engaged with the running board and with which said hooked links are adapted to engage.

3. The combination with an automobile having a running board, of eyes attached to the running board at oppositely disposed points, means for holding a milk can upon said running board comprising a collar adjustably engaging the neck of the milk can and having opposed, downwardly extending tugs adjustable as to length, a lever attached to the lower end of each tug, a hook-shaped link attached to the lever and adapted to engage said eyes, an upward movement of the lever into approximately parallel position to the tug causing a downward movement of the tug when the links are engaged with said eyes, and means for detachably holding the lever in an approximately vertical position.

In testimony whereof I hereunto affix my signature.

WALTER A. CAGLEY.
